ABSTRACT

A tool for removing couplings from tubular goods, especially for removing or installing a coupling onto a sucker rod.

The tool can be manually or motor powered in operation, and includes a barrel within which there is threadedly received a mandrel, with the mandrel having a shaft attached thereto and depending from within the barrel so as to impart rotational movement into the mandrel. Diametrically opposed to the shaft is a threaded pin portion of the mandrel which is adapted to engage the threaded box portion of the coupling of the sucker rod, so as to enable one threaded surface of the mandrel to threadedly engage a coupling while the remaining threaded surface of the mandrel threadedly engages the barrel, with a part of the coupling and the barrel being brought into abutting relationship with respect to each other in a manner to develop tremendous torsional forces.

APPARATUS FOR REMOVING COUPLINGS FROM TUBULAR GOODS

BACKGROUND OF THE INVENTION

Throughout industry there are numerous tubular goods, including solid elongated rods, pipe, and piping, as well as studs and other male and female threaded apparatus which from time to time must be removed and subsequently replaced by a new or a different but similar threaded component. This is particularly true in the oil production field, as for example, the occasional replacement of a coupling onto a sucker rod.

"Sucker rod" is a term applied to the elongated jointed metal rod which extends down hole into a borehole and into proximity of a downhole production pump so as to enable the downhole pump to be actuated from the surface of the earth by imparting reciprocal motion into the rod. Since the rod is usually several thousand feet in length, it is convenient to break the rod up into 25 foot joints, and to connect the joints of the rod together in series relationship by a special connector called a coupling.

The rod and the coupling are expensive, and the longer the sucker rod string the more durable and exotic must be the fabrication of the coupling. Accordingly, couplings vary in price in proportion to the difficulty of design, and therefore one would not ordinarily use an expensive coupling where an inexpensive one would perform equally as well.

Sucker rod is shipped from the fabricator with a selected coupling attached thereto, and with the rod being racked in side-by-side relationship and separated from one another by bolted wooden spacers so as to provide a convenient package in the form of a pallet which enhances handling thereof. Upon arriving at its destination, the coupling often is of an unwanted or undesired design, and accordingly, workmen must employ hand tools in order to substitute one type coupling for the manufacturers coupling. This substitution of couplings entails disassembly of the bundled rod so as to enable access thereto. This expedient is time consuming, laborious, expensive, and presents a distasteful job to the workmen. Moreover, where unskilled workmen perform the task, damage to the rod and coupling often occurs.

Accordingly, it is desireable to be able to substitute one coupling on a sucker rod for another in an improved manner.

SUMMARY OF THE INVENTION

This invention comprehends a tool for removing couplings from tubular goods comprising a barrel which threadedly receives a mandrel therein, with a drive shaft depending from the barrel and attached to the mandrel. A free marginal portion of the mandrel includes a second thread thereon adapted for engaging a coupling. The first thread is "left-handed" while the second thread is "right-handed."

Rotation of the mandrel by the shaft causes the second threads to make-up with the coupling, while the first thread moves the mandrel towards the shaft, thereby causing the coupling to abut a shoulder on the barrel, after which the barrel can be rotated so as to make-up or to break loose the coupling from the member to which it is normally attached.

A second embodiment of the invention includes a double clutch comprised of spaced apart shaft engaging means which permits the shaft to be actuated by a power tool in a rapid and efficient manner. When the shaft is moved toward the mandrel, the forward clutch is engaged to thereby drive the mandrel by the shaft, and when the shaft is partially withdrawn from the barrel, the second clutch is engaged so as to actuate the barrel rather than the mandrel. At the same time, the direction of rotation of the power tool can be controlled so as to manipulate the coupling in any desired manner.

It is therefore a primary object of this invention to provide a tool for making-up and breaking-out couplings associated with tubular goods.

Another object of the present invention is to provide an improved tool which facilitates the removal and replacement of couplings on sucker rod and the like.

20 A further object of this invention is to provide apparatus for assembling and disassembling couplings from tubular goods and the like in a more rapid and efficient manner.

25 A still further object of this invention is to provide improved apparatus for assembling and disassembling coupling members.

The above objects are attained in accordance with the present invention by the provision of a combination of elements which are fabricated in a manner substantially as described in the above abstract and summary.

30 Various other objects and advantages of this invention will become readily apparent to those skilled in the art upon reading the following detailed description and claims and by referring to the accompanying drawings.

BRIEF DESCRIPTION OF THE DRAWINGS

FIGS. 1 and 2, respectively, set forth an end and top view respectively, of the prior art method of shipping 40 some tubular goods;

45 FIG. 3 is a side elevational view of one embodiment of the present invention, with some parts thereof being removed therefrom, and the remaining parts being shown in section;

45 FIG. 4 shows a second embodiment of the invention, and sets forth a side elevational broken view, with some parts thereof being removed therefrom and the remaining parts being shown in section;

50 FIGS. 5, 6, and 7, respectively, are cross-sectional views taken along lines 5-5, 6-6, and 7-7, respectively, of FIG. 3.

DETAILED DESCRIPTION OF THE PREFERRED EMBODIMENTS

55 Throughout the various figures of the drawings, wherever possible, like or similar numerals refer to like or similar parts.

As seen in FIGS. 1 and 2, a pallet or bundle 10 is 60 made up of adjacent bolted together pieces of wood 11 so as to form a convenient package of sucker rod 12. Each individual rod has a coupling threadedly attached to one marginal depending end thereof, as illustrated by numerals 13 and 14. It will be noted that each adjacent rod is staggered with respect to one another so as to permit the rods to be placed closely adjacent to one another thereby conserving space.

Looking now to the details of FIG. 3, in conjunction with FIGS. 5-7, there is seen a tool, generally illustrated by the arrow at numeral 15, made in accordance with the present invention. The tool includes a shaft 16 depending in an outward or a rearward direction, and a mandrel 17 depending in an outward or a forward direction therefrom. A main body 18, hereinafter called "a barrel," is preferably made in the form of an elongated cylinder, with one marginal end portion thereof being milled at 19 into a hexagon shape so as to enable several different type wrenches to be conveniently received thereon.

A free depending marginal terminal end portion of the shaft is likewise provided with a hexagon shape in the illustrated manner indicated by numeral 20. The opposite marginal end portion of the shaft 21 is provided with a clutch pin 22 arranged laterally with respect to the tool and outwardly depending from the outer peripheral surface of the shaft. An intermediate marginal portion of the shaft cooperates with reduced diameter counterbore 23, with the tolerance therebetween being significantly controlled so as to form a suitable journal. End portion 23' of the barrel is in the form of a shoulder or a transverse face having a considerable surface area so as to effect a bearing surface, as will be better appreciated later on in the disclosure.

The mandrel includes a threaded end portion and a driven end portion. The threaded end of the mandrel includes a first thread 25 which threadedly engages a marginal inside peripheral surface of the barrel. The illustrated shoulder at 26 defines the length of the first thread, and in some instances, may merely be a groove, which also forms a second shoulder 26' from which the second threaded surface 27 of the mandrel commences. Threads 27 cooperate with and are complimentary to the indicated inside threaded portion 28' of a coupling 31. The end 28 of the coupling is adapted to abut shoulder 23' of the barrel when the tool has been properly engaged with the coupling.

An intermediate portion 29 of the mandrel is preferably enlarged at one extremity thereof so as to form a circumferentially extending skirt member having a concavity 30. The skirt is provided with diametrically opposed inwardly directed slots 31 which form a clutch portion associated with the mandrel, and which is adapted to receive clutch pin 22 therein when the shaft 16 is moved towards and into engagement with the mandrel.

Similarly there is formed within the end wall of the barrel and adjacent to the reduced diameter portion 23 a pair of diametrically opposed rearwardly extending slots 31' which depend toward shaft end 20, and then turn in a circumferential direction so as to capture clutch pin 22 therein when the pin is moved into engagement therewith.

Looking now to the details of FIG. 4, the barrel 118 is seen to enclose a marginal portion of a shaft 116. The shaft is an integral part of the mandrel. The first threaded portion of the mandrel 125 is larger than the second threaded portion so as to provide a shoulder at 126' for a purpose which will be better appreciated later on after the remainder of this disclosure is fully digested.

In operation, the tool disclosed in FIG. 3 is placed in its illustrated operative configuration with the barrel being held by the left hand and a power wrench being held in a workman's right hand. The power wrench is 5 removably affixed to the driven end of the shaft, and threaded portion 27 is placed within the box or outwardly opening interior of the coupling as the shaft is driven by the power tool in a clockwise direction. This 10 action causes the second threaded surface to make up with the coupling, and at the same time the first threaded connection is being made up with threads 34. Since threads 25 are left handed threads and the threads at 27 are right handed threads, it will be appreciated that the mandrel is being retracted within the 15 barrel, while at the same time the second threaded connection is being made up with the coupling. Accordingly, shoulder 28 of the coupling is rapidly brought into abutment with face 23' of the barrel, so that the two opposed parallel shoulders are brought 20 together in compressed relationship while the mandrel is placed in tension between the first and second threaded surfaces.

The above relationship preferably is established 25 between the tool and the coupling prior to installing or removing a coupling from a rod. Assuming the coupling is to be removed, the motor is de-energized and pulled in a rearward direction, thereby releasing the clutch pin 22 from the forward clutch and engaging the clutch pin 30 with the rear clutch part. The direction of rotation of the motor is reversed, thereby driving the barrel rather than the mandrel in a counterclockwise rotational direction. Since the mandrel has been placed under a 35 considerable tension due to the coaxing opposite threaded surfaces thereof, and since the shoulder of the coupling now engages the face of the barrel with a tremendous force, it will be appreciated by those skilled in the art that upon sufficient force being applied to the barrel, that the coupling will preferentially be released from the sucker rod prior to sufficient force being developed to break the cumulative force of friction developed between the threaded surfaces of the mandrel and the mandrel face. After the coupling has been 40 removed from the rod, the shaft is moved back into the position of FIG. 3, the wrench end of the barrel placed in any suitable holding means, and the motor again reversed so that it rotates in a counterclockwise direction, thereby breaking the surfaces 23', 28 apart. 45 Where deemed desirable, the coupling can be held by the left hand and the motor again energized so as to rapidly disengage threaded connection 27 from the coupling.

With a trifle of experience, the above can be carried 55 out in a fraction of the time that would ordinarily be required to obtain the same results while using hand tools. Furthermore, the barrel can be made any desired length so as to enable it to be placed into close proximity of any coupling 13 of the bundled rods. Accordingly, it is unnecessary to remove the rods from the bundle in order to exchange one coupling for another.

When it is desired to place a coupling onto a rod, the coupling is engaged with the second threaded surface a sufficient number of turns to assure that the threads are 60 properly aligned, or alternatively, each coupling can be manually started by hand onto each of the bundled rods. Regardless of the procedure employed, the ap-

paratus is returned to the configuration seen in FIG. 3, the shaft rotated in a clockwise direction, whereupon the mandrel moves into the barrel while threads 27 are made-up with the threaded coupling and at the same time the opposite threaded portion of the coupling is 5 made-up onto the sucker rod. Faces 23', 28 rapidly come into abutment with one another, and as the driven end of the shaft continues to rotate, the coupling will be properly torqued onto the sucker rod.

Removal of the tool from the coupling is accomplished by engaging the rear clutch, driving the barrel in a clockwise direction so as to break the force at the shoulders, after which the forward clutch is engaged and the mandrel driven in a counterclockwise direction so as to disengage the second threaded surface from the coupling.

The operation of the tool disclosed in FIG. 4 is similar to the operation of the embodiment of FIG. 3, except of course, there is no clutch available which may be actuated by reciprocal motion of the shaft.

In using the tool illustrated in FIG. 4, and in order to expedite installation of the coupling, threaded surface 125 is generously enlarged relative to the second threaded surface so as to provide a shoulder at 126'. Since the tool of FIG. 4 generally will be manually operated, this expedient facilitates installation of the couplings onto the rod for the reason that it is unnecessary to await the shoulder 28 of the coupling to abut the shoulder of the barrel.

I claim:

1. Apparatus for removing couplings from tubular goods, comprising:
a barrel, a mandrel and a drive shaft;
said barrel having means forming an elongated axially disposed passageway therethrough; said barrel further including means forming a journaled end and a threaded end, said threaded end including a threaded inside marginal peripheral surface of said passageway; said threaded end of said barrel terminating as a shoulder;
said journaled end adapted to rotatably receive a marginal portion of said drive shaft therein;
said mandrel having a threaded end and a driven end; means by which said driven end of said mandrel is attached to said drive shaft;
means forming a first and second threaded surface on said threaded end of said mandrel;
said first threaded and said second threaded surfaces being spaced apart from one another and of op-

posite threaded direction;
said first threaded surface adapted to threadedly engage the threads formed in the passageway of said barrel;

said second threaded surface adapted to threadedly engage a coupling whereby:
said shaft can be rotated to thereby impart rotational motion into the mandrel which causes the second threaded surface to engage the box of a coupling, and causes the first threaded surface to move into the barrel, thereby causing said shoulder to abut an end portion of the coupling to thereby tightly engage the tool with the coupling.

2. The tool of claim 1 and further including means forming a clutch part on said mandrel;

means forming a clutch part adjacent the journaled end of said barrel;
means associated with said shaft for selectively engaging the first and second clutch parts; whereby:
said shaft, when moved into a first position, engages the first clutch part; and, said shaft, when moved into a second position, engages the second clutch part to thereby selectively impart rotational motion into either the mandrel or the barrel.

3. The tool of claim 2 wherein said clutch part on said mandrel includes diametrically opposed slots;
and said clutch engaging means on said shaft includes a laterally disposed clutch pin affixed thereto; whereby:

when said shaft is moved into the first position the clutch pin engages the slots on said mandrel, and when said shaft is reciprocated into the second position said clutch pin engages the second said slot.

4. The apparatus of claim 1 wherein the threaded barrel includes a left handed thread; and, said first thread is a left handed thread which threadedly engages the thread on said barrel; and

the second said thread is a right hand thread which is adapted to threadedly engage the coupling member.

5. The tool of claim 1 wherein said drive shaft is an integral part of said mandrel, and further including said second threads being smaller in diameter than said first threads to thereby provide a shoulder therebetween;

said shoulder adapted to abut the shoulder of the coupling when the second thread is fully made up therewith.
